Specification of Letters Patent.

Patent

Application filed March 13, 1911, Serial No. 614,220. Renewed June 25, 1915.

To all whom it may concern:

Be it known that I, HENRY P. ROBERTS, of Boston, in the county of Suffolk and State of Massachusetts, have invented certain new and useful Improvements in Bottle-Stoppers, of which the following is a specification.

This invention relates to bottle stoppers, and more particularly to that class of bottle stoppers which are adapted to be readily applied to and removed from the neck of a bottle.

One object of the invention is to provide an improved bottle stopper which is adapted more particularly for use in temporarily closing the mouth of a bottle, after a portion of the contents of the bottle has been dispensed therefrom, although it is also adapted for use as a permanent stopper, and may be quickly and securely applied to and readily removed from the neck of the bottle.

A further object of the invention is to provide a bottle stopper which is neat in appearance, simple and durable in construction, and which lends itself readily to advertising purposes.

With the above objects in view, the invention consists in the improved bottle stopper hereinafter described and claimed, the advantages of which will be obvious to those skilled in the art from the following description.

The several features of the invention will be clearly understood from an inspection of the accompanying drawing, in which—

Figure 1 is a side elevation of a portion of a bottle with the stopper applied thereto; Fig. 2 is a front elevation of the same; and Fig. 3 is a sectional elevation of the stopper, with the neck of the bottle in dotted lines.

As illustrated in the drawing, the stopper comprises a cap 1, which may be made of sheet metal, and which holds a plug or stopper 2, of cork or other suitable material, adapted to tightly fit the mouth of the bottle 3. The stopper is held in place upon the bottle by a wire bail 4 having a semi-circular portion adapted to engage the neck of the bottle and the under side of the bead 6, which bead may be termed the "crown seal" bead since it is the bead over which the well-known crown seal caps are pressed. These beads and the necks of the bottles adjacent thereto are of uniform size on all styles of bottles having a crown seal, and

they are thus particular in connection with a stopper insuring a uniform clamping member of the

The ends of the semi-merge into loops 8 and stantly parallel to the neck of the bottle and the neck of the bottle to clamping position. Ex from the clamping loops 12 and 14 having their wardly to form pintles tively. These pintles pass of the cap 1 and enter t holding the plug securely the bail is swung down f position shown in Fig. 1 engage the swell 10 on th and as the bail is pushe of the bottle the arms 1 cause the loops 8 and 9 gage the neck of the bottlable pressure, and the se 5 is brought and held bead 6.

As a convenient means stopper from the neck o vide a knob 18, secured cap 1. This may be acco of a screw 20 passing t the cap and threaded i the knob, or the knob ma other suitable manner. 21 of the knob may be uting purposes. In some i found desirable to dispe in which case the bail 4 t the cap and used to pul the bottle.

While I have illustrat preferred embodiment c am aware that many m made therein by any pe art without departing fr invention as expressed ir fore I do not wish to b details of construction sk but

What I claim is:—

The herein described cluding a stopper memb serted into the mouth of lic cap receiving the stopper member and pi

sides thereof with corresponding pivot openings, and bail formed from a single length of wire and including a semicircular clamping portion adapted to engage the exterior bead of the bottle neck to retain the stopper securely in position, the ends of the said semicircular clamping portion terminating in vertically and oppositely disposed loops which bear frictionally against opposite sides of the bottle neck and the end portions of the said loops being extended upwardly at substantially right angles to the semi-circular clamping portion and having the

extremities thereof bent inwardly so as to engage the before mentioned pivot openings 15 in the metallic cap, the said bail being adapted to be swung into and out of operative position about the inwardly bent upper ends of the arms as pivots.

In testimony whereof I have affixed my 20 signature, in presence of two witnesses.

HENRY P. ROBERTS.
